UNITED STATES PATENT OFFICE.

JAMES H. CRARY, OF NEW YORK, N. Y.

HULL CONSTRUCTION.

Application filed May 7, 1926. Serial No. 107,424.

This invention relates to hull construction, the primary object of the invention being to so construct the hull as to permit the employment of straight frame pieces, 5 ribs and planking members which are disposed at right angles to each other so that straight boards or timbers may be used without bending, curving or otherwise shaping them.

10 A further object is to provide a hull construction in which the sides of the hull taper inwardly from their lower to their upper ends.

15 A further object is to provide a hull construction which is extremely simple and inexpensive to manufacture.

20 With these and other objects in view, the invention consists in certain novel features of construction and combinations and arrangements of parts, which will be more fully hereinafter described and pointed out in the claims.

25 In the accompanying drawings—

Figure 1 is a plan view of my improved hull;

Figure 2 is a view in transverse section on the line 2—2 of Figure 1;

Figure 3 is a fragmentary view in longitudinal section on the line 3—3 of Figure 2.

30 1 represents the keel of my improved hull having a shoe 2 thereon, the sides of the keel being recessed, as shown at 3, to receive the bottom planks 4 which are straight but which incline upwardly from the keel to the sides of the hull.

35 5 represents the bottom ribs to which the planks 4 are secured and which are also straight and extend from the keel to the sides of the hull. 6 represents the chimes 40 which are located at the sides and bottom of the hull, and 7 are side ribs which are located at right angles to the bottom ribs 5, and 8 are the frames which are also located at right angles to the bottom ribs 5. 9 indicates the side planking which is secured to the ribs 7 and frames 8 and are perfectly straight and are at right angles to the planking 45 4.

50 On the outside of the hull, at the lower edges thereof, I preferably provide cushioning bars 10, which extend substantially throughout the length of the hull.

By reason of this construction, whereby the bottom and side ribs and planking are at right angles to one another, the side walls 55 of the hull are inclined or tapered inwardly from their lower to their upper ends.

By reason of this construction I am enabled to employ absolutely straight pieces, requiring no bending, curving or cutting of 60 any sort other than cutting them into proper lengths. I am, therefore, enabled to build a hull much cheaper than is possible with hulls as heretofore made, and I provide a hull of a different shape from anything 65 heretofore known. I, therefore, do not wish to be limited to the particular construction or to other features of the hull but desire to cover broadly this novel construction and arrangement of ribs, planking and frames. 70

Various slight changes and alterations might be made in the general form of the parts described without departing from the invention and hence I do not limit myself to the precise details set forth but consider 75 myself at liberty to make such slight changes and alterations as fairly fall within the spirit and scope of the appended claims.

I claim:

1. A hull, comprising a keel, bottom ribs 80 extending upwardly at an angle to the keel and from both sides thereof, side ribs located at right angles to the bottom ribs, and straight planks secured to the bottom ribs and to the side ribs forming the hull. 85

2. A hull of the character described, having its sides tapering inwardly from their lower to their upper ends, the hull having bottom ribs, side ribs and frames located at right angles to the bottom ribs, and straight 90 planks secured to the bottom ribs, side ribs and frames.

3. A hull of the character described, having its sides tapering inwardly from their lower to their upper ends, the hull having 95 bottom ribs, side ribs and frames located at right angles to the bottom ribs, straight planks secured to the bottom ribs, side ribs and frames, and cushioning bars secured to the lower corners of the hull.

JAMES H. CRARY.
